WALL PLUG

Marshall D. Gibson, Webster Groves, Mo.

Application January 13, 1949, Serial No. 70,647

1 Claim. (Cl. 248—225)

1

This invention relates to expandible wall plugs or shells, particularly for use in providing a support on a hollow wall by which objects may be attached to the wall, or suspended. It is sometimes difficult to attach a hook, nail, screw, or the like to a hollow wall formed of such material as plasterboard, or wall board, which are not well adapted to retain nails or hooks, etc.

Heretofore wall plugs have been so formed that they will act as receivers for such supporting nails or hooks, and on March 12, 1946, United States Letters Patent No. 2,396,501 for a Wall Plug were granted to me on this type of plug. My present invention is an improvement on said Patent 2,396,501 in that my new plug will itself provide a hook from which an article may be suspended, thus rendering unnecessary the insertion of a separate hook, or nail, or the like into the plug to support an article after the plug has been applied to a wall.

Plugs as heretofore manufactured generally have been of hollow tubular construction, but the expanding portion of my plug is formed of substantially flat members which can be stamped out, or cut from small pieces of metal, and for this purpose scrap metal may be used, thus permitting a considerable saving in time, material, and cost of production.

In the drawings:

Fig. 1 is an end view of my wall plug as it appears when inserted into a wall preparatory to being expanded.

Fig. 2 is a side elevation of the wall plug shown in Fig. 1.

Fig. 3 is a side elevation of the wall plug as it appears in expanded condition attached to a wall, with its hook in operative position.

Fig. 4 illustrates a modification of the hook element of my wall plug.

Fig. 5 is a view taken on line 5—5 of Fig. 4.

Fig. 6 illustrates the modified wall plug inserted through a wall preparatory to being expanded.

Fig. 7 illustrates said modification of the invention in expanded condition on a wall and with the hook element in operative position.

In both the preferred form of the invention and the modification, the wall plug comprises a body portion integrally formed of a strip of suitable metal bent into elongated U-shape, and having a pair of legs 1 joined together by a comparatively short connecting section 2. At the center of the connecting section 2 an aperture 3 is punched out, the walls of said aperture 3 being provided with screwthreads 4. As will be

obvious from Figs. 2 and 6, the legs 1 have a slight transverse curvature and are slightly embossed outwardly at the points 5 to weaken said legs.

At points somewhat spaced away from the embossed portions 5, the legs 1 are slightly reduced in diameter to form offsets (not shown in the drawings) and a collar 6 surrounds the reduced portions and abuts against said offsets at the points 7. The ends 8 and 9 of the legs 1 project through said collar 6.

In the preferred form of the invention shown in Figs. 1, 2, and 3, the end 8 is considerably elongated and the end 9 comparatively short, and both ends 8 and 9 are bent back against the collar 6 at right angles with relation to the legs 1, as shown in Figs. 1 and 2. From what has been said it will be understood that the collar 6 is retained in position by the offsets 7 and the bent back ends 8 and 9. A washer 10 rests against the free outer surface of the ends 8 and 9, said washer being of slightly concave form so that its outer edge will firmly grip the ends 8 and 9 when the device is in operation.

In operation of the preferred form of the invention, the procedure is as follows: On either side of the aperture 3 a transverse bend is made in the metal strip forming the body of the wall plug at a slight distance from said aperture, so that the strip assumes the elongated U-shape shown in Figs. 2 and 6. A collar 6 is slipped over the free ends 8 and 9 until its abuts the offsets at the points 7, after which the ends 8 and 9 are bent back against the collar 6 until they are at right angles with respect to the legs 1 of the plug.

With the parts in this position, the plug is inserted through a hole which has been prepared for its reception in a wall W, the hole in said wall being of such diameter that the collar 6 will fit rather snugly therein. The ends 8 and 9 now rest against the outer surface of said wall, and the collar 6 lies within the wall, while the body portion of the plug comprising the legs 1 projects beyond the interior surface of the wall (Fig. 2). The washer 10 is positioned against the ends 8 and 9 so that its aperture is in registration with the space between the legs 1, and an ordinary screw S of appropriate diameter and length is inserted through said aperture and between the legs 1, and into the aperture 3 where its screwthreads engage the threads 4 of the aperture 3.

The plug is now ready to be expanded, and this is accomplished by institution screwing move-

ment to the head of the screw S with an ordinary screwdriver, and while this is being done the operator keeps the plug from turning by holding the long end 8 with one hand while manipulating the screwdriver with the other hand. As the threaded portion of the screw progresses through the threaded aperture 3, the connecting section 2 of the plug moves up toward the head of the screw, thus forcing the legs 1 to bend outwardly at their weakened embossed points 5. The screwing motion is continued until the legs 1 have been bent so that the sections 11 thereof contact and firmly grip the interior surface of the wall W (Fig. 3), and the ends 8 and 9 firmly grip its exterior surface.

With the plug affixed to the wall as described above, the end 8 is now bent upwardly, as shown in Fig. 3, to provide a hook 12 from which an article may be suspended against the wall, and as said above, this renders unnecessary the use of a separate hook or nail, since the hook 12 forms an integral part of the wall plug structure. By referring to Fig. 1 it will be noted that the end 8 is provided with two apertures 13 and 14, respectively. Should it be desired not to utilize the long end 8 as a hook, said end is sufficiently weakened by the aperture 13 to permit of its being broken off at that point, in which case it will not extend beyond the washer 10. However, when the end 8 is used to provide the hook 12, the aperture 14 serves to weaken said end at that point sufficiently to permit its being bent upwardly to form the hook.

In the modified form of the invention the ends of the legs 1 which project through the collar 6 are bent back as shown at 1', and to replace the washer 10 of the preferred form I provide an apertured element 15 comprising a disc 16, which may be round, octagonal, or of any preferred shape which is found convenient in handling. The disc has an embossed center section 17, the aperture 18 of the disc 16 extending through said section 17 (Fig. 5). The section 17 has a downwardly extending arm 19 which projects a considerable distance beyond the disc 16 as shown most clearly in Fig. 4, and has two apertures 13' and 14', respectively, similar to the apertures 13 and 14 of the preferred form.

In the use of the modified form of the invention the procedure is as follows: With the parts of the plug in the position as described in connection with the preferred form, the plug is passed through a hole prepared for it in the wall W, with portions of the legs 1 projecting through the collar 6 and beyond the wall W, said projecting portions being bent back upon the wall as shown at 1'. The element 15 is held against said wall so that the projecting ends 1' lie within the embossed section 17 thereof, the leg ends 1' having been cut off so that they are flush with the perimeter of said element 16. The screw S is passed through the aperture 18 of said element 15 and between the legs 1, and it will be understood that at this time the body of the plug with the screw therein is positioned within

the wall W in the same manner as described in connection with the preferred form.

With the element 15 resting against the outer surface of the wall and its embossed section enclosing the leg ends 1', said element is held in position by pressure of one hand of the operator on said embossed section. Screwing motion of the screw S is then instituted, and obviously this motion cannot be transmitted to the plug by virtue of the engagement of its leg ends 1' with the firmly held embossed section 17 of the element 15. The screwing operation is continued as described in connection with the preferred form, until the expanded plug has assumed the position shown in Fig. 7. As shown in this figure, the arm 19, if it is to be utilized as a hook, is bent upwardly at the aperture 14' to form the hook 12', but if preferred it may be broken off at the aperture 13'. The modified form of the invention is now in operative position, where it will serve the same purpose as the preferred form illustrated in Fig. 3.

I claim:

In a U-shaped wall plug having a longitudinal member bent intermediate its ends to form expansion strips adapted for entry in a wall opening, a sleeve surrounding said expansion strips near but spaced from their free ends, said free ends being bent outwardly at right angles to said sleeve and against the outer face of the wall, the expansion strips being weakened at predetermined points so that they will bulge outwardly against the under face of the wall when expanding pressure is applied to the intermediate bent portion of said longitudinal member, and a screw for applying said pressure positioned between longitudinal sections of said longitudinal member and threaded in said intermediate bent portion, the improvement comprising means for preventing turning of said longitudinal member when said screw is turned, said means comprising an apertured washer positioned between the head of the screw and the outwardly bent portions of said longitudinal member, said washer having a central embossed portion and a depending lug formed integral therewith, said embossed portion enclosing and interlocking with the outwardly bent portions of the longitudinal member, said lug having a weakened section to permit ready severance of the lug at the weakened section.

MARSHALL D. GIBSON.
